UNITED STATES PATENT OFFICE

2,333,025

ANGLE DRILL

Gottfried J. Mayer, Buffalo, N. Y.

Application June 30, 1941, Serial No. 400,438

8 Claims. (Cl. 77—7)

My invention relates to an angle drill, and more particularly to a drill of this type which is to be attached to the chuck of an ordinary or master drill, although the source of power used to operate the drill may be directly applied to the driving shaft or prime mover of this angle drill.

Many places are encountered in or on objects where holes are to be drilled which ordinary or master drills cannot be used for; for example, when drilling holes in recessed places or places adjacent upstanding flanges or ledges.

It is therefore one of the objects of my invention to provide an angle drill in which the driving shaft or prime mover can be entered and secured in the chuck of an ordinary or master drill, and which is of comparatively small size so that it may be operated in close quarters or adjacent what ordinarily would be considered obstructions to an ordinary or master drill, or what may be termed a conventional drill.

A further object of my invention is to provide an angle drill which may be employed as an accessory to a master drill, or which may itself be used as a master drill; its design and construction, however, being such that it is particularly adapted as an adjunct to a conventional or master drill for use in places inaccessible to the latter.

A still further object of my invention is to provide an angle drill which, as an accessory to a master drill, assures uniform rotation for the drill-bit during operation, and furthermore, which by reason of its construction, practically eliminates lateral or radial stresses of the moving parts of the drill within their bearings, thus assuring longer life and greater efficiency.

With the above and other objects in view to appear hereinafter, my invention consists in the novel features of construction and in the arrangement and combination of parts to be hereinafter described and more particularly pointed out in the appended claims.

In the drawing,

Fig. 1 is a side elevation of my improved angle drill.

Fig. 2 is a longitudinal section through the same, a portion of the drill being shown in elevation.

Fig. 3 is a top view of the same.

Fig. 4 is a front view of the same.

Fig. 5 is a detached perspective view of the intermediate shaft or connector link between the driving and driven shafts of the drill.

Fig. 6 is a perspective view of one of the cou-

pling elements connecting the intermediate shaft or link with the driving and driven shafts of the drill.

Fig. 7 is a detached perspective view of the shell or casing of the coupling.

Fig. 8 is an enlarged section taken on line 8—8, Fig. 1.

Angle drills have previously been used as accessories to master drills, but by reason of the fact that such drills require a connection between two shafts arranged at an angle to each other and such connections as now used cause intermittent speed in the rotation of the driven shaft, the operating parts of the drill become quickly worn, due to lateral or radial stresses set up in the bearings of the drill. Such stresses are materially augmented under continued use of the drill and replacements of worn parts are required at short intervals. Applicant's invention has been designed to overcome such objectionable features.

To overcome such objections, I have designed my improved angle drill, which comprises a frame or support 9 so formed that it serves as a handle, and with this in mind, an opening 10 is formed through this frame or support to enable one or more fingers of the guiding hand to be passed therethrough while grasping the handle. The opening 10 serves as a finger-hold so that the support or handle can be grasp with one hand and the device or drill thus directed to the work to be performed; oftentimes in locations not conveniently accessible by other means. The device may therefore be termed a one-hand device, because of its form and compactness, and therefore it will be apparent that means other than the opening 10 may be provided for serving as a means to firmly grasp the device in one-hand so that it will not become displaced from the work during operation. The frame or support, or more definitely the handle, is reduced in width from one end to the other, or in other words from its outer end to what may be termed its inner end, with the marginal portions along one edge at obtuse angles. Along the upper, marginal portion of this handle a shaft bore 11 is formed which is comparatively long to provide a good bearing for the driving shaft 12 of the device. This shaft has one end reduced and screw threaded, as at 13, and its other end is adapted for entrance into the chuck of a master drill, so that upon operating the latter the driving shaft 12 will be rotated. If desired, the source of power employed for operating the master drill may be applied directly to this driving shaft.

The handle or support 9 is provided with an

oil hole 14 extending from its upper edge into the shaft bore 11, so that the shaft can be properly oiled.

The driving shaft 12 also has a stop collar 15 pressed or otherwise secured thereon so as to bear against one end of the handle, as at 16. This collar is so positioned that only the screw-threaded reduced end 13 of the shaft projects from the opposite end of the handle or support, as clearly shown in Fig. 2.

17 designates a shaft coupling considered as a whole, and this comprises an inner member 18, which may be termed the coupling element or coupling proper, and an outer member 19 which is in the form of a sleeve utilized as an enclosure shell, into which the coupling proper is pressed. The fit between the two members of the complete coupling is such that movement relatively of these members cannot take place.

The inner member 18 or coupling proper is bored out from one end so as to form an end wall 20 at the other end thereof in which a screw-threaded opening 21 is axially formed. This opening receives the reduced screw-threaded end 13 of the driving shaft 12, or prime mover as it may be termed, the screw-threads being so formed that during operation of the shaft the tendency of the coupling is to tighten itself upon said shaft. From the open end of the inner member or coupling proper, diametrically opposite slots 22 are formed, these slots extending approximately to the end wall 20. Therefore, when the outer member or enclosure shell 19 is pressed firmly over the inner member or coupling proper 18, the slots 22 in the latter are covered and are not visible except from the open end of the complete coupling.

The support or handle 9 is so constructed that a second bore 23 is formed therein, preferably at an obtuse angle to the bore 11, and this bore 23 is also utilized as a shaft bearing for what may be termed the driven shaft, designated by the numeral 24. This support is also provided with an oil opening 25 leading to the bore 23, so that the driven shaft 24 may be properly oiled. The lower or outer end of the driven shaft 24 is enlarged, as at 26, and provided with a downwardly or outwardly opening axial bore 27 which is screw-threaded or otherwise provided with means to retain a drill-bit entered therein. This enlargement therefore serves the purpose of a chuck, and may be termed an adapter chuck. The inner end of this driven shaft is reduced and screw-threaded, as at 28, and only this screw-threaded reduced end projects from the bearing portion of the support or handle in which the shaft is journaled. This end 28 of the shaft is threaded into a second coupling similar to the coupling connected to the driving shaft 12. For this reason the parts of this second coupling member are designated by the same numerals as those constituting the coupling member attached to the driving shaft.

From the foregoing it will be apparent that the bearings for the shafts 12 and 24 are arranged along marginal portions of the handle which are disposed at an obtuse angle to each other and are separated by an intervening space.

29 designates an intermediate shaft, which may more aptly be termed a connector link connecting the driving shaft 12 with the driven shaft 24. This intermediate shaft or link is provided at opposite ends with spherical terminals 30, each being entered in the coupling element 18 of a coupling 17, and each of these spherical terminals

is provided with diametrically opposite studs 31 which are entered in the slots 22 of said coupling element. Such connection of the intermediate shaft or link with the couplings may be termed universal joints. The intermediate portion of the intermediate shaft or link is enlarged as at 32 for the purpose of increasing the strength of the same while providing spherical terminals at opposite ends capable of entering the coupling 17 without unduly enlarging the latter; and since this intermediate shaft or link is subjected to considerable strain, the advantage of this enlargement will be apparent, especially since it provides the necessary rigidity for this member. The intermediate shaft or link with the coupling elements at opposite ends thereof occupy the intervening space between the shaft bearings.

By reason of the studs 31 being entered in the slots 22 of the couplings 17, the intermediate shaft or link 29 is caused to rotate upon rotation of the driving shaft 12, and in turn causes rotation of the driven shaft 24, with assurance that the uniformity of rotation applied by the source of power to the driving shaft will be transferred to the driven shaft, in contra-distinction to present-day methods of connection provided between the driving and driven shafts of angle drills, in which, during each complete revolution of the driving shaft, a speeded up partial and a retarded partial movement is imparted to the driven shaft. Therefore, during each rotation or cyclic movement of the driven shaft, intermittent speed is provided, which slows up the work, and applies severe lateral or radial stresses on the driven shaft. This results in the wearing of parts, necessitating re-boring of the support or handle 9 and substitution of replacement shafts or larger diameters, or the addition of bushings in order to receive a driven shaft of regulation diameter, especially since tools of this kind are subjected to severe usage in many places. The parts of applicant's device subject to wear, such as the couplings and the intermediate shaft or link, can be easily replaced at a trifling expense, and even such parts will immeasurably outlast angle drills now in use.

Having thus described my invention, what I claim is:

1. An angle drill, comprising an elongated support or handle having a shaft bearing along one of its longitudinal marginal portions and a second at its end disposed at an angle to the first-mentioned bearing, opposing ends of said bearings being separated by open space, a shaft 55 in the first-mentioned of said bearings, a coupling applied to said last-mentioned shaft at the adjacent end of its bearing, a shaft in the other bearing, a coupling applied to the end of said shaft in opposed relation to said first-mentioned coupling, and an intermediate shaft having a universal joint connection with both of said couplings.

2. An angle drill, comprising a support or handle having shaft bearings disposed at an obtuse angle to each other, a driving shaft journaled in one of said bearings and having a stop collar in contact with the outer end of said bearing and a connector end extending from the inner end of said bearing and abutting against the latter, a driven shaft journaled in the other of said bearing and having an adapter chuck at its outer end in contact with the outer end of said last-mentioned bearing and a connector end extending from the inner end of said bearing and abutting against the latter, a link interposed between

the connector ends of said shafts, and universal connections between the ends of said link and the connector ends of said driving and driven shafts.

3. An angle drill, comprising a support or handle having shaft bearings disposed at an obtuse angle to each other, a driving shaft journaled in one of said bearings and having a stop collar in contact with the outer end of said bearing and a reduced screw-threaded terminal projecting from the inner end of said bearing, a driven shaft in the other of said bearings having an enlarged portion serving as an adapter chuck in contact with the outer end of said last-mentioned bearing and a reduced screw-threaded terminal projecting from the inner end of said bearing, couplings threaded onto the reduced screw-threaded inner terminals of said shafts, each coupling opening to their inner ends and having stud-receiving slots formed therein, and an intermediate shaft provided with diametrically opposite projecting studs at each end entered into the stud-receiving slots of the respective couplings.

4. An angle drill, comprising a support or handle having shaft bearings disposed at an obtuse angle to each other, a driving shaft journaled in one of said bearings and having a stop collar in contact with the outer end of said bearing and a reduced screw-threaded terminal projecting from the inner end of said bearing, a driven shaft in the other of said bearings and having an enlarged portion serving as an adapter chuck in contact with the outer end of said last-mentioned bearing and a reduced screw-threaded terminal projecting from the inner end of said bearing, couplings threaded onto the reduced screw-threaded inner terminals of said shafts, each coupling opening to its inner end and having stud-slots formed therein, and an intermediate shaft provided with spherical terminals and studs projecting from diametrically opposite points of said spherical terminals and entered into the stud-slots of said couplings.

5. An angle drill, comprising a support or handle having shaft bearings disposed at an angle to each other, a driving shaft journaled in one of said bearings and having a stop collar bearing against the outer end of said bearing and a reduced screw-threaded terminal extending from the inner end of said bearing, a driven shaft journaled in the other of said bearings and having an adapter chuck in contact with the outer end of said last-mentioned bearing and a reduced screw-threaded terminal extending from the inner end of said bearing, a coupling applied to each of said reduced screw-threaded terminals, each coupling comprising an inner member having an axial screw-threaded opening to receive the reduced screw-threaded terminal of its respective shaft and slots in its peripheral wall extending inwardly from its outer end, each inner

member of said couplings having an outer member applied thereover to cover said slots, and a link between said couplings having spherical ends entered in said couplings and studs projecting from diametrically opposite points of said spherical ends and entered into the slots of the inner members of said couplings.

6. An angle drill, comprising an integral hand-grasped support or handle having a finger-hold enabling the handle to be grasped in one hand and shaft-bearings disposed at an angle to each other and separated from each other at adjacent ends by an intervening space, a driving shaft journaled in one of said bearings and held against longitudinal movement therein toward said space, a driven shaft in the second bearing having a chuck at its outer end to hold said driven shaft against longitudinal movement toward said space, couplings applied to the opposing ends of said shafts in said space and abutting against said bearings to prevent longitudinal movement of said shafts in directions away from said space, and a link connecting said couplings by means of universal joints within said couplings.

7. An angle drill, comprising an integral support or handle having shaft bearings at an angle to each other, one of said bearings being arranged along one of the marginal portions of said support or handle and the other along a portion of the handle at an angle to said marginal portion, a driving shaft journaled in one of said bearings and having a stop collar in contact with the outer end of said bearings and a connector end extending from the inner end of said bearing and abutting thereagainst, a driven shaft journaled in the other of said bearings and having an adapter chuck at its outer end in contact with the outer end of said last-mentioned bearing and a connector end extending from the inner end of said bearing and abutting thereagainst, and a link interposed between the connector ends of said shafts and having terminals co-acting with said connector ends to form universal joints between said links and said connector ends.

8. An angle drill, comprising a support or handle reduced in width from one end thereof to the other and having marginal portions along one edge thereof spaced apart and disposed at an obtuse angle to each other, shafts journaled in said spaced-apart marginal portions, a universal-connection connecting adjacent ends of said shafts and serving to prevent movement longitudinally of said shafts away from each other, means on one of said shafts for preventing longitudinal movement thereof in an opposite direction, and a chuck at the outer end of the other shaft to prevent movement of the latter longitudinally toward said universal couplings.

GOTTFRIED J. MAYER.
